G. R. SHANKLIN.
VALVE DEVICE FOR ACETYLENE LAMPS AND THE LIKE.
APPLICATION FILED JUNE 10, 1918.

Patented Nov. 23, 1920.

By *Shanklin* Atty.

UNITED STATES PATENT OFFICE.

GEORGE R. SHANKLIN, OF SPRINGFIELD, ILLINOIS.

VALVE DEVICE FOR ACETYLENE-LAMPS AND THE LIKE.

1,359,755.

Specification of Letters Patent. Patented Nov. 23, 1920.

Application filed June 10, 1918. Serial No. 239,171.

To all whom it may concern:

Be it known that I, GEORGE R. SHANKLIN, a citizen of the United States, residing at Springfield, in the county of Sangamon and

5 State of Illinois, have invented certain new and useful Improvements in Valve Devices for Acetylene-Lamps and the like, of which the following is a description.

My invention belongs to that general class 10 of devices provided with valves which are particularly designed to control the flow or feed of the fluid to the calcium carbide, or its equivalent. It has for its object the production of a simple, durable and effective device 15 for the purpose described that is not likely to clog up and that can be readily freed from any spent carbide or other matter that may adhere thereto. To this end, my invention consists in the novel construction, 20 arrangement and combination of parts herein shown and described and more particularly pointed out in the claims.

In the drawings, wherein like reference 25 characters indicate like or corresponding parts,

Figure 1 is a central vertical section through an acetylene lamp of the class known as miners' lamps;

Fig. 2 is a similar section of the lower 30 portion of the fluid tube and valve, enlarged;

Fig. 3 is a transverse section on line 5—5 of Fig. 2;

Fig. 4 is a similar section on line 6—6 of 35 Fig. 2;

Fig. 5 is a sectional view similar to Fig. 2, showing a modification;

Fig. 6 is a transverse section on line 3—3 of Fig. 5.

40 In the drawings, 1 represents the water chamber and 2 the carbide chamber of a lamp of the kind described, the two being connected at 3 by the usual screw threaded construction. 4 is a filling opening in the water chamber, and 5 is a cap therefor. The gas generated in the chamber 2 is conducted to and escapes through the tube 6, which when in use is provided with the usual gas tip, and a reflector if desired.

50 7 is the water tube carried by the water chamber and extending downward therethrough and well into the carbide chamber, so as to be positioned in the carbide when in use. The lower end of the water tube 7 is 55 formed with a valve seat 8. Rotatably secured to the lower end of the water tube 7 is

the sleeve 9, which, in the form shown, is at its upper end bent inward as at 10 to engage a circumferential groove or indentation 11 formed in the tube 7 for that purpose. 60

12 is a rotatable valve stem carrying upon its lower end a valve 13 coöperating with the valve seat 8. The sleeve 9 extends a suitable distance below the valve and is provided with slotted openings 14 substantially 65 in line with the valve seat, by which the fluid released by opening the valve may escape outwardly. The valve also is preferably of such a size or shape as compared to the sleeve 9, as to permit the fluid to escape between the two downwardly. 70

In that embodiment of the invention illustrated in Figs. 1, 2, 3 and 4, the valve is provided with a downwardly depending extension 15, which, in the preferred form, 75 is substantially square or other regular shape, loosely fitting the interior of the sleeve so that as the sleeve and the valve are rotated in relation to one another, the said extension 15 will serve to grind off and 80 clear the lower end of the tube of any incrustations thereupon. This depending extension 15 may, in some instances, be dispensed with, with very satisfactory results, and in that embodiment of the invention 85 illustrated in Figs. 5 and 6, the valve 13 is devoid of such extension.

The upper end of the stem 12 is secured to a thimble 16 which is screw threaded in the upper end of the tube 7, and the stem 90 is bent downward or outward as at 17 so as to afford convenient means for rotating the valve stem and thimble.

The operation of the device is apparent. The rotation of the valve will serve to crush 95 and clear the device of any incrustations forming at the valve seat 8, and the sleeve 9 may readily be turned by the thumb and finger of the operator to clear the lower end of the device from such incrustations. In 100 the form illustrated in Figs. 1, 2, 3 and 4, the extension 15 serves a similar purpose in clearing the device of any accumulation of incrustations without in any way stirring or agitating the carbide in the carbide chamber. 105

Having thus described my invention, what I claim as new and desire to secure by Letters Patent is:—

1. In a device of the kind described, a 110 depending fluid tube provided with a valve seat upon its lower end, and a rotatable sleeve mounted upon the lower end of the

- tube and extending below the valve seat, in combination with a rotatable valve stem within the tube provided upon its lower end with a valve arranged to coöperate with the seat on the lower end of the tube and means for permitting the escape of fluid between the two, the said sleeve being of a length to project below and constitute a surrounding casing for the valve at all times.
- 10 2. In a device of the kind described, a depending fluid tube provided with a valve seat upon its lower end, and with a sleeve mounted upon the lower end thereof and extending below the valve seat, said sleeve being provided with slotted openings in line with the valve seat, in combination with a rotatable valve stem positioned within the tube and carrying upon its lower end a valve adapted to coöperate with the valve seat to control the flow of fluid through the tube, the said sleeve being so connected with the tube that it is free for relative rotatable movement but fixed against longitudinal movement, substantially as described.
- 15 3. In a device of the kind described, a depending fluid tube provided with a valve seat upon its lower end, a sleeve mounted upon the lower end of the tube for free relative rotatable movement and fixed against longitudinal movement and extending below the valve seat, said sleeve being provided with slotted openings in line with the valve seat, in combination with a rotatable valve stem positioned within the tube and carrying upon its end a valve arranged to coöperate with the valve seat to control the escape of fluid from the tube, said valve being provided with a downwardly extending part adapted to clear the free end of the sleeve of any foreign matter accumulating therein.
- 20 4. In a device of the kind described, a depending fluid tube provided with a valve seat upon its lower end and a rotatable sleeve fixed against longitudinal movement mounted upon the lower end of the tube and extending below the seat, in combination with a rotatable valve stem within the tube provided upon its lower end with a valve arranged to coöperate with the valve seat and spaced from the sleeve to permit the escape of fluid between the two, said sleeve being adapted at all times to project below the valve parts, substantially as and for the purpose described.
- 25 5. In a valve construction for acetylene

lamps and the like, the combination of a depending fluid tube provided at its lower end with a valve seat, a valve stem loosely projecting through the tube and terminating at its lower end in a valve to engage the said seat, and a sleeve loosely positioned on the tube and projecting below the valve seat as well as the valve parts, said sleeve having an opening adjacent the valve seat, and a direct interlocking engagement between the tube and sleeve permitting relative rotatable movement between these parts.

6. A device of the kind described comprising a container, a fluid tube depending from the top thereof and provided with a valve seat at its lower end, an adjustable valve stem projecting through the tube and terminating at its lower end in a valve of substantially the diameter of the tube and adapted to engage the valve seat of the tube, said tube having adjacent its lower end a circumferential recess, an elongated sleeve loosely positioned on the lower end of the tube and having an inwardly disposed part adjacent its upper end to engage in said circumferential recess whereby to permit relative rotation of the sleeve and to prevent relative longitudinal movement, said sleeve being of a length to project below and constitute a surrounding housing for the valve, and said valve being free from projecting parts extending below said sleeve.

7. A device of the character described comprising a container, a fluid tube depending from the top of the container, said tube having adjacent its lower end a circumferential guideway, a valve stem projecting through the tube and terminating at its lower end in a valve to engage the lower end of said tube, a sleeve loosely fitted over the lower end of said tube and having a part to engage said guideway, whereby to permit of rotatable movement of the sleeve and to prevent endwise movement, said valve having a downwardly extending projecting part, and said sleeve being of a length to at all times project below and constitute a guard for said projecting part of the valve.

In testimony whereof, I have hereunto signed my name in the presence of two subscribing witnesses.

GEORGE R. SHANKLIN.
